JAMES S. STEWART, OF PHILADELPHIA, PENNSYLVANIA, ASSIGNOR TO HIMSELF, AND THOMAS OLIVER AND J. C. YEAGER, BOTH OF CHICAGO, ILLINOIS, AND T. M. BUTLER, OF NOBLESVILLE, INDIANA.

PANORAMIC CAMERA.

No. 893,819.

Specification of Letters Patent.

Patented July 21, 1908.

Application filed January 2, 1907. Serial No. 350,451.

To all whom it may concern:

Be it known that I, JAMES S. STEWART, citizen of the United States, residing at Philadelphia, in the county of Philadelphia and 5 State of Pennsylvania, have invented certain new and useful Improvements in Panoramic Cameras; and I do hereby declare the following to be a full, clear, and exact 10 description of the invention, such as will enable others skilled in the art to which it appertains to make and use the same.

This invention relates to a novel construction in a panoramic camera, the object being 15 to provide an efficient and very compact device of this character in which the operating mechanism is entirely inclosed and is disposed in what would constitute waste space on the instrument and in which the area of exposure, and the time and strength thereof 20 may be readily and easily adjusted, and consists in the features of construction and combinations of parts hereinafter fully described and claimed.

In the accompanying drawings illustrating 25 my invention: Figure 1 is a side elevation of a panoramic camera constructed in accordance with my invention, the outer casing being removed. Fig. 2 is a top plan view of the same, the casing being removed. Fig. 3 30 is a top plan view of the same, the casing being removed and part of the top and bottom plates being broken away. Fig. 4 is a bottom plan view of the same, the casing being removed. Fig. 5 is an elevation of the same 35 on the side opposite to that illustrated in Fig. 1, the casing being removed. Fig. 6 is a detail view of a turn table forming part of the operating mechanism. Fig. 7 is a detail view of a governor employed. Fig. 8 is a 40 fragmentary detail view in elevation showing means employed for determining the area of exposure of the film. Fig. 9 is a bottom plan view of a plunger employed. Fig. 10 is a detail view in elevation of a lever employed 45 same being shown in bottom plan and in reverse of its actual position. Fig. 11 is a top plan view of a plate forming part of the regulating means employed. Fig. 12 is a front elevation of the camera in its casing. Fig. 50 13 is a view in side elevation of the camera in its casing, the latter being partly broken away. Fig. 14 is a detail fragmentary plan section on the line 14—14 of Fig. 12 the bottom plate being broken away and all operating mechanism except certain levers and

parts connected with and operated thereby being omitted. Fig. 15 is a fragmentary detail vertical longitudinal section showing a stop lever employed.

One object of my invention is to provide a 60 panoramic camera which occupies no more space than is occupied by the ordinary box or fixed focus camera so that the same may be easily carried and handled, and in which the operating mechanism is entirely inclosed 65 in the box or casing, such mechanism being disposed within spaces within the box or casing rendered available by the employment of traveling film.

A further object of my invention is to provide simple and efficient means whereby the 70 length or area of each exposure, the time of such exposure, and the strength thereof may be readily adjusted and controlled by means accessible from the exterior of the casing. 75

A further and important object of my invention is to provide simple and efficient means for causing the film to travel at a speed exactly proportioned to the speed of travel of the lens in order to produce a clear 80 continuous picture all parts of which are uniformly exposed and in which no breaks or blurs are produced by reason of variations in relative speed of travel of the film and lens.

Owing to the fact that in panoramic cameras, the film travels relatively to the lens or vice versa, and that only a very narrow vertical strip thereof is exposed at a time, the camera body proper may obviously be made very narrow so that for example, in a 4x5 85 fixed focus camera the body of the camera need be only an inch or less in width, thus leaving spaces on each side thereof within the casing to receive the operating mechanism. Cameras of this character are employed only for landscape and similar work 90 so that the fixed focus type answers best all the requirements thereof. These facts I have taken advantage of in the embodiment of my invention, and, as shown in Fig. 2, 100 contract the camera body at its rear end portion to form a narrow light shaft 16 in alignment with the lens and over the rear end of which the film travels, the latter leaving the reel or spool 50 and being wound upon the 105 reel or spool 51 as will be hereinafter described.

The camera body is revolvably mounted upon the shaft of a turn-table 33 consisting of a relatively large spur-gear which is provided in the center of its lower face with a 110

threaded opening 33^c which is adapted to receive the thumb-screw of the supporting tripod to maintain said turntable rigid with the latter. The shaft 33^b of said spur-gear is 5 rigid therewith and is loose relatively to the camera body which is suitably pivotally mounted thereon. Meshing with said spur-gear is a spur-pinion 32^a which is rigid with a spur gear 32 revolubly mounted on a stud 10 67 disposed in the end of an arm 32^b pivotally mounted on the shaft of the spur gear 33, said arm having a segmental projection 56 at its free end extending to one side thereof. On the bottom wall of the camera is a Y- 15 shaped metal frame 48 having legs at two of its free ends by means of which it is secured thereto, one arm thereof being provided with a segmental slot 69 concentric with said shaft of said spur-gear 33 and through which a set- 20 screw 32^c entering a threaded opening in the free end of said segmental projection 56 passes, said set-screw serving to hold said arm 32^b in any desired position relatively to said frame 48. The said spur-gear 32 meshes with the spur pinion 31 disposed on 25 the lower end of a vertical shaft 66, said spur gear being removable and being adapted to be replaced by spur-gears of varying diameters for reasons hereinafter set forth. The 30 said arm 32^b enables the position of the spur-gear 32 to be adjusted to accord with different sizes of said spur pinions 31. Said shaft 66 carries a bevel-gear 29^b which meshes with the bevel pinion 29^c on the horizontal 35 shaft 29 suitably journaled in bearings on the base-plate 15 of the camera. At the other end of said shaft is a bevel pinion 29^a which meshes with a bevel pinion 23 on a second horizontal shaft 29^d, the latter carrying a 40 spur pinion 22 by means of which said shaft is geared to the spring motor 18 through the intermediacy of the spur gears 20, 21 and 19, the shafts of said gears 20 and 21 and the drive-shaft of the motor being journaled at 45 one end in the frame 17^a. The said motor 18 is thus geared to said shaft 66 and said turntable 33, and by reason of the rigid relation of the latter to the supporting tripod, the motor, when in operation will revolve the 50 camera thereon. On said shaft 66 above the bottom plate 15 of the camera, is a drum 46 between which and a spring pressed idler 47 the film is engaged and fed. The said film is taken from the spool 50, passed over an 55 idler 49 and between the drum 46 and idler 47 and wound upon the spool 51, the latter being disposed upon the shaft of a friction clutch 54 of suitable construction which is geared to said shaft 66 through the inter- 60 mediacy of the gears 30, 30^a and 30^b, said clutch being adapted to exert only sufficient friction on said spool 51 to revolve the same and the shaft 52 but not sufficient to draw or stretch the film, being merely intended to 65 take up the film as rapidly as the same is fed

by said drum 46. Said spool 51 is, however, held against rotation relatively to said shaft 52. The shaft of the idler 47 is journaled at its ends in the free ends of arms 47^d of the vertical shaft 47^a, the latter carrying an arm 70 47^b below the bottom plate 15 which is connected at its free end with one end of a tension spring 47^c connected at its other end with a rigid part of the framework. The motor 18 is disposed upon one side of the 75 light-shaft 16 and is geared to a horizontally disposed ball-governor on the opposite side of said light-shaft through the intermediacy of said shaft 29^d, the pinion 23^a and gears 24, 25 and 26 and interposed pinions. The said 80 governor is of well-known construction comprising the two pivoted arms carrying the balls or weights 28 and connected between their ends by means of suitable links with a cross head on a collar 27 longitudinally movable on the shaft 28^a on which is a spiral compression spring 29 against the action of which the said collar is moved as the balls are spread by centrifugal force. The shaft 85 28^a is journaled at one end in the frame 17. 90

Before proceeding further with the description of the operating mechanism I desire to call attention to the fact that the lens 45 of the camera is always open, while adjacent the rear end of the light-shaft 16 is disposed a 95 leaf 55 of greater width than said light-shaft and mounted at one end on a shaft 55^a the axis of which is practically flush with one side wall of said light-shaft. The said leaf 55 serves simultaneously as shutter and diaphragm the term "diaphragm", being herein used in the sense that said shutter serves to determine the number of light rays concentrated upon the film when exposed by controlling the width of the opening through 100 which the light penetrates to the film, although said shutter does not perform all of the functions of the diaphragm as ordinarily understood in photography. At its lower end said shaft 55^a carries an arm 55^b having a 105 projection at its free end which enters a longitudinal slot in one end of a lever 55^c, pivotally mounted between its ends on the framework and at its other end connected with a link 35 engaged and normally held at one 110 limit of its movement by a spiral spring 35^a the latter serving to maintain the shutter 55 normally open. On said link 35 is a projection 35^b at one side which is adapted to engage the free end of a depending arm 58 pivotally connected at its other end with the starting lever 43, said free end of said arm passing through a slot in the bottom wall of the camera and being disposed in the path of 115 and adapted to hold said link 35 at the rearward limit of its movement against the action of said spring 35^a, to maintain the shutter 55 closed. Said starting lever 43 is pivotally mounted between its ends on a part of 120 the framework, the forward end thereof pro- 125

130

jecting through a slot 43^a in the front wall of the camera and its other end being provided with a projection 43^b bearing on the periphery of said disk 27 of the governor, being 5 maintained in peripheral contact with the latter by means of a spring 59 and acting as a brake to prevent operation of the motor. The said arm 58 is pivotally secured to said last-named end portion of the lever 43 between 10 the ends thereof so that by depressing the forward end of said lever said arm 58 will be raised out of the path of said projection 35^b and the link 35 will thus be moved forward by the spring thus opening the shutter 15 55 and throwing said projection 35^b into the path of the lower end of the arm 58 to maintain said lever 43 out of contact with the disk 27, and thus permitting the motor to start.

Attention is now directed to Fig. 12, illustrating 20 the front elevation of the camera. It will be seen that below said slot 43^a is a lateral slot 42^a the upper wall of which is provided with recesses 42^b above which consecutively appear numerals "6, 8, 10, 12, 15, 25 20 and 30" respectively and through said slot the end of a lever 42 projects by means of which the speed of the motor is governed so as to cause the same to completely revolve the camera in substantially the number of 30 seconds represented by the aforesaid numerals impressed above said recesses 42^b. For example, if the light is such as to require the longest possible exposure the lever 42 is turned to register with the recess "30" 35 whereupon the motor is retarded as subsequently explained to require substantially thirty seconds to completely revolve the camera, and proportionately long time for any fraction of a revolution.

40 In the lower right hand corner of the front plate of the camera is a lateral slot 70 through which the end of a lever 39 projects, said slot being provided in its upper wall with recesses 38 above which consecutively 45 appear the numerals "1" to "6" inclusive, the said lever 39 controlling the number of film surfaces of given area each to be exposed or, in other words, determining the length of the picture. For example if a film 50 five inches wide is used and each exposure is four inches in length, then if said lever 39 registers with recess "1", the film will travel until four inches thereof has been exposed, and if set to register with recess "3", the 55 film will be caused to travel until twelve inches thereof have been exposed. Below said slot 70 is a slot 71 through which one end of a lever 40 projects, the upper wall of said slot being provided with recesses 72 60 above which consecutively appear the numerals "1" to "5" inclusive, the said lever 40 serving to control the "diaphragm" opening of the camera, that is, it controls the arc through which the shutter 55 is 65 swung when opened so as to regulate the

width of the slot through which the light penetrates to the film from one-eighth to five eighths of an inch, for example, each of said numerals "1" to "5" representing the smallest and multiples of the smallest opening through which exposure is effected. 70

The manner in which the respective levers 42, 39 and 40 control the operating mechanism I will now describe in detail.

The lever 42 is pivotally secured to a part 75 of the frame work at its innermost end and is provided between its ends with an arm 42^a which at its free end is disposed in the path of the disk 27 of the governor in the latter's movement against the action of the 80 spring 28^a the position of said arm 42^a being determined by the position of said lever 42 and in its turn determining the degree of opening of the governor and consequently its speed of rotation. That is to say that if 85 said arm 42^a is disposed so far inwardly of the normal position of said disk 27 as to enable the weights 28 to spread almost to their limit, then the motor (and governor) will have attained and will maintain a relatively high speed, but if said arm is so disposed relatively to said disk 27 as to prevent the said weights 28 from spreading to any considerable degree, then the speed of the 90 motor will obviously be retarded by reason 95 of the friction to which the said disk is subjected when forced into contact with the said projection by the spreading of said weights.

The lever 39 controls the length of film exposed in the following manner. Referring to 100 Figs. 1 and 3, it will be noted that said turntable or spur-gear 33 is provided on its upper face with a plurality of pins 33^a disposed spirally with reference to the axis of said turntable, said pins serving as stops to determine 105 the arc through which the camera travels. On the frame work of the latter a depending arm 34 is pivotally mounted which at its free end passes through a slot in the bottom wall of the camera disposed substantially radially 110 relatively to the axis of rotation of said camera and in which said arm 34 swings substantially radially relatively to the said axis. The said arm terminates at a point above the plane of the upper ends of said pins 33^a and 115 carries a small depending plate 34^a hung on the lower end of a flat spring 34^b secured to said arm 34 between the ends thereof and serving to normally maintain said plate 34^a 120 out of contact with said arm 34 and spaced from the latter a distance greater than the diameter of said pins 33^a. The free end of said plate 34^a projects below the plane of the upper ends of said pins and accordingly into the paths of the latter, being disposed in the 125 path of any particular pin by adjusting said arm 34 either toward or away from the axis of rotation of the camera. The lever 39 is pivotally mounted between its ends at 39^a on a part of the frame work and at its inner end 130

is pivotally secured to a longitudinally slotted sliding plate 37, through the slots 37^a of which screws pass into the bottom wall of the camera, said screws serving as guides for said plate. The latter is movable in a direction parallel with the plane in which said arm 34 swings, and is provided with a projection 37^b having a slot 37^c disposed transversely to the slots 37^a and through which the lower ends 5 of the arm 34 and plate 34^a project, so that by turning said lever 39 and throwing said plate 37 in either direction the said arm 34 will be swung into the paths of the different pins 33^a. The said arm 34 is also free to 10 swing forward of the position shown in Fig. 1 and projects into the recess between two arms 35^c on the link 35 the rearmost arm 35^c serving to carry the free end of said arm 34 and the plate 34^a forward with said link 35. 15 On the latter is a pin 35^d to which one end of the spring 35^a is secured, said pin serving also to coact with the lever 40 to control the "diaphragm" opening of the camera. The 20 said lever 40 is pivotally secured between its ends at 40^a to a part of the framework and at its inner end is provided with a projection 40^b the extreme free end of which is stepped to provide five shoulders 40^c which are adapted to be disposed in the path of said pin 35^d 25 to limit the forward movement of said link 35, the latter being adapted to travel its full limit when said stepped end of said lever 40 is turned entirely out of the path of said pin 35^d and to travel only a fraction of its limit 30 in accordance with the degree to which said lever 40 is turned in a direction to throw said stepped end thereof into the path of said pin. 35

The operation of my camera is as follows: The camera proper is telescopically inserted 40 into the casing 74, the latter being open at its forward end and said camera being held in place therein by means of a suitable spring catch 44. Before inserting the same, however, the film spool 50 is mounted on the pivots provided therefor, one of said pivots being disposed on the free end portion of a flat spring 60 in the usual manner. The web on which the film is mounted is then trained over the idler 49 and drum 46 against which 45 it is pressed by the idler 47 and secured in the usual manner to the spool 51. After inserting the camera proper into its casing, the film is advanced by revolving the spool 51 by means of a key adapted to engage the square 50 shank 53 of the shaft 52 which is loose with relation to the spur-gear 30^b and clutch 54 until the number "1" appears opposite the opening 73 in the casing, said opening having red glass disposed therein. At this time the 55 front edge of the film will be disposed opposite the rear end of the light shaft 16.

The motor having been wound up by means of a key in the usual manner, and the instrument mounted on the tripod, all is in 60 readiness to take a picture. Assuming that

the day is very bright and sunny and a view found which the operator desires to photograph, the next steps consist in adjusting the time and intensity of exposure and the length of the picture. The day 70 being bright, the duration of exposure must be minimum. Accordingly the lever 42 is set to register with the recess 42^b of the slot 42^a numbered "6" thereby so positioning the arm 42^d thereof as to permit the governor to open fully and thus allow the motor to run at maximum speed. Next the lever 40 is set to register with the recess 72 of the slot 71 numbered "1" thereby throwing the lug or projection of the stepped inner end 75 thereof which is farthest removed from the pivot of said lever 40 into the path of the pin 35^d of the link 35 and thus limiting the forward movement of the latter and consequently the opening of the shutter 55 to 80 the minimum. Next the lever 39 is set to register with one of the recesses 38 of the slot 70 according with the multiple of exposure areas which the photograph is desired to cover. Assuming that the operator 85 desires to photograph the view through an arc of about 180 degrees the said lever is set to register with recess 38 numbered "3" the picture thus covering a film area equal to three 4x5 exposures, or a total of 5x12 90 inches. All being now in readiness, the starting lever 43 is depressed, thus releasing the brake from the motor and throwing the arm 58 out of the path of the projection 35^b of the link 35 which instantly springs 95 forward and opens the shutter 55. At the same time, the projection 35^c of the link 35 throws the arm 34 the plate 34^a of which is now disposed in the path of one of the pins 33^a of the turn-table 33, forward, 100 the said arm 34 having been previously moved laterally into the path of the proper pin by adjustment of the lever 39. The camera now revolves at a uniform speed, the lens traveling in one direction and the 105 film traveling with equal speed in the opposite direction so that in effect the film remains fixed with relation to the tripod while the lens travels. Each part of the surface of the film is thus progressively exposed in exact ratio to the speed of travel of the lens and thus each part of the view being photographed is recorded on the film, no part being repeated or omitted. The film must travel through a great 110 distance in the same length of time as the lens. During this time the arm 58 rests upon the projection 35^b and maintains the brake released from the motor. As the 115 camera approaches the other end of the arc of travel to which it has been limited by adjustment of the lever 39, the pin 33^a which is in reality disposed in the path of the plate 34^a of the arm 34 strikes the latter and throws said plate against said arm 34 120 125 130

thus stopping the latter. The camera continues to revolve, however, against the action of the spring 35^a thus throwing said arm 34 and said link 35 back to the rearward limits of their movement, thereby closing the shutter 55 and throwing the projection 35^b of the link 35 out of the path of the arm 58 which by the action of the spring 59 drops and thus also throws the 10 brake on the motor, although the latter is stopped as soon as said arm 34 reaches the rearward limit of its movement. Should the operator now desire to take another picture, he must, after placing his tripod 15 in proper position, move the lever 39 to another position depending upon the desired length of his next picture. If he desires the latter to cover only a single 4x5 area, he moves said lever to register with 20 recess "4". If he desires to take a picture covering three 4x5 areas, he moves said lever to register with the recess "6". If he desires his next picture to cover six 4x5 areas, he must move said lever to either of 25 the recesses "2" or "4" and then back to recess "3". This is necessary in order to permit the plate 34^a to be sprung to the forward limit of its movement and be brought behind and out of the path of the 30 pin 33^a with which it was in engagement. During this time the motor is held fast by the brake but by now again depressing the lever 43 the motor is started and causes the camera to make a complete revolution, 35 thus producing a picture extending through an arc of three hundred and sixty degrees.

The speed of travel of the film is controlled entirely by the drum 46 the surface speed of which is equal to the speed of travel of the 40 lens, this being determined by the size of pinion 31 employed. The use of compensating gears usually employed in cameras of this character is consequently entirely avoided and the troubles due thereto are obviated. 45 The said pinion 31 is rendered interchangeable so that lenses of different focal lengths may be employed. If for example a lens having a focal length of seven inches is substituted for a lens having a focal length of 50 six inches, such lens must be set one inch farther from the plane of travel of the film than the six inch lens. Hence, the substituted lens travels farther through a given angle and consequently the gearing controlling the 55 movement of the film must be changed so that the latter will travel the additional distance in the same time as it is covered by the new lens, a smaller pinion 31 being, therefore, substituted.

60 I claim as my invention:

1. In a panoramic camera, a camera body revoluble on its support and equipped with film feeding means, a motor common to said camera body and said film feeding means to 65 actuate the same in unison, a governor con-

trolling said motor, hand-lever actuated means controlling said governor to regulate the speed of said motor, and means maintaining said hand-lever at predetermined points between the limits of its movement, whereby the period of exposure of the film is 70 regulated.

2. In a panoramic camera, a camera body revolubly mounted on its support, a motor actuating the same, speed regulating means 75 disposed in operative relation to said motor, a brake controlling said speed regulating means, a hand-lever controlling said brake, said hand-lever and said camera body being equipped with coacting means for maintaining said lever at different points between the limits of its movement to maintain said motor at different predetermined speeds to regulate the period of exposure of the film, film feeding means disposed on said camera body 80 and variable gearing between the latter and said motor whereby a length of film corresponding to the distance of travel of the camera lens is fed during the same interval.

3. In a panoramic camera, a camera body 90 revolubly mounted on its support, a motor actuating the same, speed regulating means disposed in operative relation to said motor, a brake controlling the same, a hand-lever controlling said brake, said hand-lever and 95 said camera body being equipped with coacting means for maintaining said lever at different points between the limits of its movement to maintain said motor at different predetermined speeds to regulate the period of exposure of the film, film feeding 100 means disposed on said camera body, and gearing between the latter and said motor.

4. In a panoramic camera, a camera body revolubly mounted on its support, film feeding means disposed thereon, a motor common to said camera body and said film feeding means to actuate the same in unison, speed regulating means disposed in operative relation to said motor, and a hand-lever actuated 105 brake controlling said speed regulating means, said hand-lever and said camera body being equipped with coacting means for maintaining said lever at different points between the limits of its movement to maintain 110 said motor at different predetermined speeds to regulate the period of exposure of the film.

5. In a panoramic camera, a camera body revolubly mounted on its support, film feeding 120 means disposed thereon, a motor common to said camera body and said film feeding means to actuate the same in unison, speed regulating means disposed in operative relation to said motor, a hand-lever actuated 125 brake controlling said speed regulating means, said hand-lever and said camera body being equipped with coacting means for maintaining said lever at different points between the limits of its movement to main- 130

- tain said motor at different predetermined speeds to regulate the period of exposure of the film, and stopping and starting means disposed in operative relation to said motor.
- 5 6. In a panoramic camera, a camera body revolubly mounted on its support, a motor actuating the same, speed regulating means disposed in operative relation to said motor, and including a revolute member actuated 10 through the intermediacy of centrifugal force to move longitudinally on its support, an adjustable stop disposed in the path of said revolute member, and a hand-lever controlling said stop, said hand-lever and 15 said camera body being equipped with co-acting means for maintaining said lever at different points between the limits of its movement to maintain said motor at different predetermined speeds to regulate the 20 period of exposure of the film.
7. In a panoramic camera, a camera body revolubly mounted on its support, a motor actuating the same, speed regulating means disposed in operative relation to said motor 25 and comprising a ball governor, a disk actuated thereby and adapted to be moved longitudinally on its support as the arms of said governor diverge, an adjustable stop disposed in the path of said disk, and a hand-lever controlling said stop, said hand-lever and said camera body being equipped with co-acting means for maintaining said lever at different points between the limits of its movement to maintain said motor at different 30 predetermined speeds to regulate the period of exposure of the film.
8. In a panoramic camera, a camera body revolubly mounted on a support, a spur-gear rigid on said support and disposed concentric with the axis of rotation of said camera body, a motor carried by the latter, a vertical shaft actuated thereby and carrying a pinion at its lower end, said pinion being interchangeable, an idle spur-gear meshing with said pinion, an adjustable member carrying said idle gear, and a pinion rigid with said idle gear and meshing with said first named spur-gear to impart motion to said camera body.
- 45 9. In a camera, a single member comprising simultaneously the diaphragm and shutter disposed behind the lens, regulating means disposed in operative relation to said member to limit the opening movement thereof, a hand-lever controlling said regulating means, a spring actuating said member to move the same in one direction, and means actuating said member to move the same in the other direction against the action of said spring.
- 50 10. In a camera, a single member comprising simultaneously the diaphragm and shutter disposed behind the lens, regulating means disposed in operative relation to said member to limit the opening movement thereof, a hand-lever controlling said regulating means, a spring actuating said member to move the same in one direction, and power actuated means actuating said member to move the same in the other direction against the action of said spring.
- 55 11. In a camera, a single member comprising simultaneously the diaphragm and shutter disposed behind the lens, regulating means disposed in operative relation to said member to limit the opening movement thereof, a hand-lever controlling said regulating means, a spring actuating said member to move the same in one direction, and power actuated means actuating said member to move the same in the other direction against the action of said spring, said last named means being hand-controlled.
- 60 12. In a panoramic camera, a camera body revolubly mounted on its support, said body having a narrow light-shaft in alinement with the lens, film feeding means disposed on said camera body, a shutter disposed in said light-shaft and controlling the penetration of rays to said film, regulating means disposed in operative relation to said shutter to control the opening movement thereof, a motor common to and actuating said camera body and said film feeding means, actuating means disposed in operative relation to said shutter to open and close the same, said last-named means including said motor, and hand-actuated means common to said motor and said shutter-actuating means to control the movements thereof.
- 65 13. In a panoramic camera, a camera body revolubly mounted on its support, film feeding means carried thereby, a light-shaft disposed in alinement with the lens and laterally past the rear end of which the film travels, a shutter in said light-shaft controlling the exposure of said film, a motor common to and actuating said camera body and said film feeding means, actuating means including said motor disposed in operative relation to said shutter, and hand-controlled controlling means common to and disposed in operative relation to said motor and said shutter, and serving when actuated to simultaneously start the motor and open said shutter.
- 70 14. In a panoramic camera, a camera body revolubly mounted on its support, film feeding means carried thereby, a light-shaft disposed in alinement with the lens and laterally past the rear end of which the film travels, a shutter in said light-shaft controlling the exposure of said film, a motor common to and actuating said camera body and said film feeding means, actuating means including said motor disposed in operative relation to said shutter, and hand-controlled controlling means common to and disposed in operative relation to said motor and said shutter, and serving when actuated to simultaneously start the motor and open said shutter, speed regulating means disposed in opera-

tive relation to said motor, and a hand-lever controlling the same.

15. In a panoramic camera, a turn-table, a camera body revolvably disposed thereon, a motor carried by said camera body, film feeding means disposed on said camera body, gearing between said motor and said turn-table through the intermediacy of said film feeding means, stops disposed on said turn-table at varying distances from the axis of rotation of said camera body, a stop-lever disposed on the latter, a hand-lever controlling said stop-lever to throw the same into positions to bring any one of said stops into the path thereof, and hand-controlled starting means disposed in operative relation to said motor.

16. In a panoramic camera, a turn-table, a camera body revolvably mounted thereon, a motor carried by said camera body, a plurality of stops disposed on said turn-table at varying distances from the center thereof and at intervals peripherally thereof, a motor actuating said camera body, an adjustable stop-lever on the latter, and a hand-lever controlling said stop-lever to throw the same into the path of any one of said stops on said turn-table to limit the movement of said camera to any desired arc.

30 17. In a panoramic camera, a turn-table, a camera body revolvably mounted thereon, a motor carried by said camera body, a plurality of stops disposed on said turn-table at varying distances from the center thereof and at intervals peripherally thereof, a motor actuating said camera body, an adjustable stop-lever on the latter, and a hand-lever controlling said stop-lever to throw the same into the path of any one of said stops on said turn-table to limit the movement of said camera to any desired arc, film feeding means disposed on said camera body and actuated by said motor, a shutter disposed between the film and the lens in said camera, a spring maintaining said shutter normally open, and operative connection between said shutter and said motor whereby the former is operated against the action of said spring.

18. In a panoramic camera, a turn-table, a camera body revolvably mounted thereon, a motor carried by said camera body a plurality of stops disposed on said turn-table at varying distances from the center thereof and at intervals peripherally thereof, a motor actuating said camera body, an adjustable stop-lever on the latter, and a hand-lever controlling said stop-lever to throw the same into the path of any one of said stops on said turn-table to limit the movement of said camera to any desired arc, film feeding means disposed on said camera body and actuated by said motor, a shutter disposed between the film and lens in said camera, a spring maintaining said shutter normally

open, and operative connection between said shutter and said motor whereby the former is operated against the action of said spring, said last named connection including said stop-lever.

19. In a panoramic camera, a turn-table, a camera body revolvably mounted thereon, a motor actuating the same, adjustable stopping means disposed on said camera body, stops on said turn-table coacting with said stopping means to limit the arc of movement of said camera body with relation thereto, a hand-lever controlling said stopping means, a shutter, spring actuated means holding said shutter normally open, a trip-lever holding said shutter closed against the action of said spring, a brake engaging a part driven by said motor to normally maintain the latter stopped, hand-controlled means common to said brake and said trip-lever to simultaneously release the same, and means actuated by said motor through the intermediacy of said stopping means closing said shutter against the action of said spring.

20. In a panoramic camera, a turn-table, a camera body revolvably mounted thereon, a motor actuating the same, adjustable stopping means disposed on said camera body, stops on said turn-table coacting with said stopping means to limit the arc of movement of said camera body with relation thereto, a hand-lever controlling said stopping means, a shutter, spring actuated means holding said shutter normally open, a trip-lever holding said shutter closed against the action of said spring, an adjustable stop disposed in operative relation to the shutter opening devices to limit the opening movement thereof, a brake engaging a part driven by said motor to normally maintain the latter stopped, hand controlled means common to said brake and said trip lever to simultaneously release the same, and means actuated by said motor through the intermediacy of said stopping means closing said shutter against the action of said spring.

21. In a panoramic camera, a turn-table, a camera body revolvably mounted thereon, a motor actuating the same, adjustable stopping means disposed on said camera body, stops on said turn-table coacting with said stopping means to limit the arc of movement of said camera body with relation thereto, a hand-lever controlling said stopping means, a shutter, spring actuated means holding said shutter normally open, a trip-lever holding said shutter closed against the action of said spring, an adjustable stop disposed in operative relation to the shutter opening devices to limit the opening movement thereof, a hand-lever controlling said stop, a brake engaging a part driven by said motor to normally maintain the latter stopped, hand-controlled means common to said brake and said

trip-lever to simultaneously release the same, and means actuated by said motor through the intermediacy of said stopping means closing said shutter against the action of said 5 spring.

22. In a panoramic camera, a turn-table, a camera body revolvably mounted thereon, stopping means disposed in operative relation to said camera body and said turn-table 10 to limit the movement of said camera body thereon, hand-controlled means controlling said stopping means, film feeding means disposed on said camera body, a motor common to said camera body and said film feeding means to simultaneously actuate the same, speed regulating means disposed in operative relation to said motor, a hand-lever controlling the same, a shutter, spring actuated means maintaining said shutter normally open, a trip-lever disposed in operative 15 relation to and maintaining said spring actuated means normally in position to close said shutter, an adjustable stop disposed in the path of said spring actuated means to 20 limit the opening movement of said shutter, a hand-lever controlling said stop, said motor and said stopping means being adapted to close said shutter against the action of said spring actuated means, a brake disposed in 25 operative relation to the motor to maintain the same normally at rest, and hand controlled means common to said brake and said 30

trip-lever to simultaneously release the same to start the motor and open said shutter.

23. In a panoramic camera, motor actuated film feeding devices comprising a driven drum over which the film is trained, a take-up reel, and a driven spring controlled friction clutch disposed in operative relation to and actuating said take-up reel, the latter 40 being capable of free movement relatively to said clutch.

24. In a panoramic camera, motor actuated film feeding devices comprising a driven drum over which the film is trained, a spring-pressed idler holding said film firmly 45 in frictional contact with said drum, a take-up reel, and a driven spring actuated clutching member engaging said reel.

25. In a panoramic camera, motor actuated film feeding devices comprising a driven drum over which the film is trained, a spring-pressed idler holding said film firmly 50 in frictional contact with said drum, a take-up reel, and a driven spring-controlled clutch disposed in operative relation to and actuating said take-up reel.

In testimony whereof I have signed my name in presence of two subscribing witnesses.

JAMES S. STEWART.
